INFRARED OVEN CONSTRUCTION

Wesley Wilson, Chicago, Ill.

Application February 26, 1947, Serial No. 731,115

7 Claims. (Cl. 219—34)

1

The present invention relates generally to an oven construction utilizing electric lamps as a source of heat, and has particular reference to an oven construction of the general type disclosed in my Patent No. 2,317,426 issued April 27, 1943, in which a plurality of lamp fixtures, each supporting a longitudinal row or series of infrared lamps, are hinged together or otherwise interconnected for relative angular adjustment to provide a lamp bank which may be used singly or in multiple to constitute a radiant heat oven.

One of the objects of the present invention is to provide an elongated fixture containing a row or series of heat lamps which is in the form of a trough having longitudinally extending shields back of the lamps providing a closed exterior devoid of open spaces through which if present an undue loss of heat would be experienced.

Another object is to provide a lamp fixture of the foregoing character in which the shields and the means for supporting the lamp sockets are susceptible of being insulated against the escape of heat to the exterior by conduction and radiation.

Another object is to provide lamp fixtures which are substantially closed back of the lamps, and which are adapted for interconnection to permit relative angular adjustment so as to provide a heat bank capable of being assembled in different shapes, the contiguous fixtures of the bank being always in substantial close longitudinal edge to edge relation in all relative angular positions whereby to provide a substantially closed assembly devoid of open spaces between the fixtures through which if present heat would freely escape.

A further object is to provide a heat bank composed of a plurality of elongated lamp fixtures pivotally interconnected in longitudinal edge to edge relation, and each comprising a lamp housing trough of substantial triangular internal section, whereby the contiguous fixtures subtend external spaces of triangular section adapted to receive and accommodate both insulating material and electric leads for supplying electrical energy, the insulation and the leads being arranged in the external spaces in relation to the pivotal connections between the fixtures so as not to interfere with relative angular adjustment of the fixtures.

Another object is to provide elongated lamp fixtures adapted to be interconnected in longitudinal edge to edge relation for relative angular adjustment in a composite heating bank in which the ends of the fixtures present flat unobstructed

2

surfaces located outwardly beyond the connecting means between the fixtures and the means for supporting the bank, so that an aligned series of banks may be assembled in substantially closed end to end relation and with the contiguous lamps of successive fixtures spaced approximately the same as the lamps within the fixtures to provide a sectional oven of any desired length.

A further object is to provide means for supporting a plurality of banks of the foregoing character in opposed relation to define a tunnel shaped oven, which means permits each bank to be swung from operative position easily and conveniently into a predetermined open position to facilitate inspection and servicing.

Other objects and advantages will become apparent as the description proceeds.

In the accompanying drawings,

Fig. 1 is a fragmentary end elevational view of 20 a tunnel oven constructed of lamp banks embodying the features of the present invention.

Fig. 2 is a fragmentary perspective interior view, on a reduced scale, of one of the banks of lamps adapted to constitute one side of the oven.

Fig. 3 is a fragmentary horizontal sectional view taken along line 3—3 of Fig. 1, and illustrating the details of one of the lamp fixtures forming part of the lamp bank.

Fig. 4 is a fragmentary transverse sectional view taken through two juxtaposed fixtures of the bank.

Fig. 5 is a fragmentary perspective view of one end of the lamp fixture.

Fig. 6 is a fragmentary perspective view of a back rail forming part of the fixture.

Fig. 7 is a fragmentary transverse sectional view illustrating one manner of providing heat insulation.

Referring more particularly to the drawings, 40 the infrared oven, constituting the exemplary embodiment of the present invention, preferably comprises two opposed banks 10 and 11 of lamps 12 which may be selectively adjusted or oriented in position to provide heating tunnels of various transverse sizes and shapes, either symmetrical or unsymmetrical, in accordance with the requirements of the work to be heated or dried. Each of the heating banks 10 and 11 comprises a plurality of elongated lamp fixtures 13 which

50 are arranged in parallelism, and which are pivotally interconnected for relative angular disposition transversely in straight alignment or any desired curved section. In common use, the lamp fixtures 13 are supported in horizontal position longitudinally, but may be disposed in different

angular positions transversely. Each of the fixtures 13 is provided with a longitudinal series of spaced electric sockets 14 for the reception of electrical heat lamps 12 of any suitable type, for example, either sealed reflector lamps or bare lamps. The individual fixtures 13 may be constructed and stocked in various widths and with different numbers of and differently spaced lamp sockets 14 so that by selective assembly to produce the lamp banks 10 and 11 any desired overall heat pattern may be obtained. It will be understood that this heat pattern may be either uniform or variegated.

Each lamp fixture 13 (see particularly Figs. 3 to 5), in the preferred form, comprises a longitudinal back rail or socket rail 16, two laterally diverging heat shields or reflectors 17 extending longitudinally along opposite side edges of the rail, and two transverse mounting plates 18 rigidly interconnected with the rail and the shields to constitute all of these elements a rigid or unitary horizontal frame or trough structure for a tier or row of the lamps 12. More particularly, the back rail 16, preferably is provided in the form of a channel bar having an inner base wall 19 formed with a longitudinal series of spaced openings 20 for the reception of the lamp sockets 14, and having spaced parallel outwardly projecting legs 21. To provide means for mounting the lamps sockets 14 in position, the base wall 19 of the rail 16 is stamped or formed at diametrically opposite sides of each opening 20 and longitudinally of the rail with offset pads 23. Each socket 14 is provided with lateral ears 24 adapted to be seated against and secured to the pads 23 by means of screws 25. Preferably, the mounting surfaces of the pads 23 are transversely inclined, and the pads for alternate sockets 14 are inclined in opposite directions so that the lamps 12 will be alternately tilted in opposite directions sidewise of the rail 16.

The shields or reflectors 17 may be provided in various shapes, and in the present instance consist of generally flat sheet metal plates secured at opposite ends to the transverse mounting plates 18 and disposed against the inner face of the wall 19 to diverge laterally therefrom. The spaced innermost longitudinal edges of the reflector plates 17 are bent reversely to form external marginal beads or curls 26, and the adjacent outermost longitudinal edge portions are flexed or curved to define an approximately parabolic transverse section.

The transverse mounting plates 18 preferably are alike in construction, and each comprises a central triangular wall portion 27 of a size and shape to close the associated end of the fixture 13. The opposite end portions of each plate 18 extend beyond the reflector shields 17, and are stamped or formed into inwardly offset parallel relation to the wall 27. Thus, the offset end portions of the plate 18 constitute supporting ears 28 which are interconnected with the triangular wall portion 27 by means of laterally bent flanges 29 defining ledges in the inner face of the plate 18. The ends of the shields 17 overlap the ledges 29 and are secured thereto by bolts 30. Preferably, the supporting ears 28 are crimped inwardly adjacent the apex of the wall portion 27 so as to provide spaced parallel locating ribs 31 snugly receiving and coacting with the legs or flanges 21 of the back rail 16 to confine the latter in centered position. Suitable angle brackets 32 are secured to the inner faces of the wall 19 at opposite ends of the rail 16 and to the inner faces of the transverse supporting walls 27 as by means

of bolts 33, thus completing frame assembly of the fixture.

It will be evident from the foregoing that each of the lamp fixtures 13, which preferably are alike in construction, consists of a simple frame structure, the component elements of which may be inexpensively formed out of sheet metal stock and readily assembled, and which is substantially closed back of the lamps 12 so as to prevent the undue loss of heat to the back or exterior of the lamp banks 10 and 11. By reason of the inwardly offset ears 28 for mounting and connecting purposes, the extreme ends of the fixture 17 are defined by the wall portions 27, and hence are substantially free of external obstructions and protuberances. Consequently, a series of lamp banks may be longitudinally aligned in end to end relation, with the adjacent end wall portions 27 of the fixtures 13 of successive banks in closely spaced and substantially abutting relation, thereby permitting the construction of ovens of any desired length by the assembly of standard bank units.

In assembling the fixtures 13 of each lamp bank 10 or 11, the ears 28 of the supporting plates 18 of adjacent fixtures are disposed in overlapping relation and pivotally interconnected for relative angular adjustment, one ear of each plate being offset inwardly of the wall portions 27 more than the other ear by a distance corresponding approximately to the thickness of the metal. In each instance, the pivot may comprise a bolt or rivet 34 located substantially at the apex of the triangular external space 35 subtended by the outer surfaces of the reflector plates 17 of any two contiguous fixtures. The marginal curls 26 of the reflectors 17 are so curved and located with reference to the pivot 34 that they will remain substantially in rolling contact to close effectively the spaces between the contiguous longitudinal edges of the adjacent fixtures in any position of relative angular adjustment.

To provide means for locking the fixtures 13 rigidly in selected positions of adjustment, the ears 28 of each overlapping set are formed with registering slots 36 arcuate about the connecting pivots 34, and are adapted to be clamped together by means of clamp washers 37 on bolts 38 extending through the overlapping ends of the slots 36 and adapted to be tightened by means of wing nuts 39. Preferably, crimps or serrations 36a are formed in the ears 28 along the slots 36 so as to provide a secure grip, and graduations 36b are provided to indicate the degree of adjustment. Since the ears 28 are inwardly offset, the clamping means will not project outwardly beyond the flat end wall portions 27 of the fixtures 13, and hence will not interfere with the assembly of a series of lamp banks in close abutting relation, as when assembling the banks in a long sectional oven.

The closed reflector arrangement of the assembled fixtures 13 of each bank 10 or 11 lends itself conveniently to the housing of the electric wiring for the lamps, and to the efficient heat insulation of the oven. Thus, the electric wiring may comprise a bus bar or cable 47 extending crosswise of the bank of fixtures 13, and comprising a series of connected sections 48 extending respectively from any one back rail 16 to the next. To accommodate the electrical connections, the side legs 21 of each rail 16 are formed with openings 49 to which the ends of the sheathing of the cable sections 48 are connected by

means of suitable fittings 50. The supply lead wires 51 of the cable extend from each section 48 across the interior of the back rail 16 to the next section. Feed wires 52 are tapped to the lead wires 51 and extend along the interior of each back rail for connection in parallel to the respective lamp sockets 14. A cover 16a may be removably secured in place to enclose the wires 51 and 52 within the rail 16. Preferably, the openings 49 in the opposite side legs of each back rail 16 are staggered, and each cable section 48 is coiled or bent into the triangular space 35 between the adjacent fixtures 13 substantially up to the pivots 34 so as to provide slack permitting relative angular adjustment of the latter.

The closed character of the lamp bank serves to prevent the loss of heat to the exterior by reason of radiation or convection. It additionally permits the use of heat insulation for preventing loss of heat to the exterior by means of conduction through the back rails 16 and reflector plates 17. While heat insulation of any suitable character may be provided, preferably, sheets 53 of asbestos or other suitable insulating composition may be disposed over one surface of each of the shields 16, and preferably over the outer surfaces thereof in the external triangular spaces 35 between the contiguous fixtures 13. The sheets 53 may be confined in position in any suitable manner, as by inserting the inner edges in the curls 26 and the outer edges between the back bars 16 and the outer curved edge portions of the shields 17. In the slightly modified form of Fig. 7, the shields 17 are entirely flat and formed with reverse curls 26a at the outer edges, and the insulating sheets 53 are confined in position by the curls 26 and 26a. The sheets 53 thus terminate adjacent the pivots 34 so as to avoid any interference with the angular adjustment of the fixtures 13 relative to each other. Under certain conditions, additional bulk heat insulating material (not shown) may be inserted in the outer spaces 35.

Each lamp bank 10 or 11 of assembled fixtures 13 may be supported in any suitable manner, as for example, from a pair of spaced upright floor standards 40 (see Fig. 1). In the present instance, each standard 40 is shown as comprising a vertical tube or rod 41 rigidly anchored at the lower end to a horizontal floor plate 42, and rigidly supported in upright position from the plate by means of an angle brace 43.

Two parallel horizontal cross arms 44 are adapted to be adjustably clamped in vertically spaced relation to the upper end portion of each tube 41 and to be clamped at their free ends to one of the fixtures 13 of the supported bank, it being understood that the other fixtures will be supported in assembled relation therewith by reason of the adjustable connections therebetween. In the present instance, each arm 44 is clamped to the tube 41 by means of a curved strap 45 adapted to be tightened by means of bolts 46. Preferably, the free or outer ends of the arms 44 are detachably connected to an intermediate or central fixture 13 of the lamp back. The attachment means, conveniently, may comprise the same bolts 38 and wing nuts 39 which are used for clamping this fixture and the adjoining fixtures in selected position of adjustment. It will again be evident that by reason of the offset ears 28, the supporting arms 44 will be located inwardly of the extreme end wall portions 27 of the fixtures.

The supporting standards 40 lend themselves 75

to quick and convenient separation of the opposed banks 10 and 11 of the oven for servicing. To this end, the floor plate 42 of each standard 40 is hinged at the outer edge to an anchor plate 56 rigidly bolted to the floor. Consequently, the standard 40 can be swung laterally of the bank either into upright position as shown in full outline or outwardly as indicated in dotted outline, but cannot be swung inwardly beyond upright position. To automatically limit the extent of swinging movement, and thereby determine the open position, the two opposed standards 40 of each set are interconnected at points immediately above the angle braces 43 by means of a slack tie member, such as a chain 57. Thus, either of the banks 10 or 11 may be tilted or swung outwardly away from the other bank until the slack in the chain 57 is taken up, and thereupon the other bank will serve through the chain to support the first bank in open inclined position. Within the broad aspects of the invention the tie member for each bank may be anchored to any fixed or restraining support. As shown in Fig. 7, the lamp bank 10 has an individual tie member 57 anchored at its remote end to the floor instead of to an opposed bank.

It will be evident that I have provided a new and improved lamp fixture which is substantially closed back of the lamps, and of which a plurality of fixtures may be adjustably connected in a lamp bank of substantially closed construction. The means for joining the elements of each fixture, for assembling the fixtures in a bank and for supporting the bank are set back from the ends of the fixtures so that a series of banks may be arranged in close end to end relation without substantial open space therebetween and to maintain substantially the same center distances between the end lamps of contiguous aligned fixtures as are provided between the lamps within each fixture. Due to the closed character of the banks and the use of insulation in the external spaces thereof, undue loss of heat is prevented.

I claim as my invention:

1. In a lamp bank, in combination, a plurality of parallel elongated lamp fixtures, each fixture being trough-shaped and supporting a longitudinal series of lamp sockets therein and having transverse mounting plates at opposite ends, each mounting plate having ears at its opposite ends and exteriorly of the fixture which are offset inwardly from the ends of said fixture, means pivotally connecting the adjacent fixtures at the contiguous edges of the troughs for relative angular adjustment, said ears of adjacent fixtures being disposed in overlapping relation and formed with registering slots arcuate about the pivotal connections and being crimped along the edges of said slots and provided with graduations along the said slots, and clamping means extending through said slots of the overlapping ears for securing said fixtures in selected positions of angular adjustment, said clamping means being disposed inwardly of the extreme ends of said fixtures so that successive banks of fixtures may be disposed in close end to end relation.

2. In a lamp bank, in combination, a plurality of parallel elongated lamp fixtures, each fixture being trough-shaped and supporting a longitudinal series of lamp sockets therein and having transverse mounting plates at opposite ends, each mounting plate having ears at its opposite ends and exteriorly of the fixture which are offset inwardly from the ends of said fixture, means pivotally connecting the adjacent fixtures at the

contiguous edges of the troughs for relative angular adjustment, said ears of adjacent fixtures being disposed in overlapping relation and formed with registering slots arcuate about the pivotal connections, and clamping means extending through said slots of the overlapping ears for securing said fixtures in selected positions of angular adjustment, said clamping means being disposed inwardly of the extreme ends of said fixtures so that successive banks of fixtures may be disposed in close end to end relation.

3. In a lamp fixture, in combination, an elongated back rail in the form of a channel having a longitudinal base wall and spaced parallel side legs and being formed in said wall with a longitudinal series of spaced openings, a plurality of lamp sockets mounted respectively in said openings, two elongated shields extending along said wall respectively at opposite sides of said sockets and diverging laterally therefrom to define a lamp trough of generally triangular section, and two transverse mounting plates closing opposite ends of said trough, each of said mounting plates having a central triangular outer wall portion and having inwardly offset ends defining ears connected to said central wall portion by transverse ledges, the ends of said shields being seated against and secured to said ledges, each of said mounting plates at the apex of said central wall portion being crimped inwardly to define spaced parallel ribs receiving and locating the legs of said rail, and means for connecting the ends of said rail to said central wall portion.

4. In a lamp fixture, in combination, an elongated back rail in the form of a channel having a longitudinal base wall and spaced parallel side legs and being formed in said wall with a longitudinal series of spaced openings, a plurality of lamp sockets mounted respectively in said openings, two elongated shields extending along said wall respectively at opposite sides of said sockets and diverging laterally therefrom to define a lamp trough of generally triangular section, and two transverse mounting plates interconnected with the opposite ends of said rail and shields to secure these elements in assembled relation and serving to close opposite ends of said trough, each of said mounting plates having a central triangular outer wall portion and having inwardly offset ends defining ears connected to said wall portion by transverse ledges, the ends of said shields being seated against and secured to said ledges.

5. In a lamp fixture, in combination, an elongated back rail in the form of a channel having a longitudinal base wall and spaced parallel side legs and being formed in said wall with a longitudinal series of spaced openings, a plurality of lamp sockets mounted respectively in said openings, two elongated shields extending along said wall respectively at opposite sides of said sockets and diverging laterally therefrom to define a lamp trough of generally triangular section, and two transverse mounting plates interconnected with the opposite ends of said rail and shields to secure these elements in assembled relation and serving to close opposite ends of said trough, the opposite longitudinal edges of said shields being reversely bent to define exterior oppositely-opening grooves and sheets of heat insulating material lining the exterior surfaces of said shields and projecting at their edges into said grooves as a retaining means therefor.

6. In an infrared oven bank, the combination comprising a plurality of parallel elongated fixtures each fixture being trough-shaped and supporting electrical fittings for the reception of heating elements therein, each two adjacent fixtures being disposed with their contiguous longitudinal edges in substantially closed relationship and being pivotally interconnected for relative transverse angular adjustment about an axis extending along and located medially of said edges, each of said fixtures being provided at opposite sides of the troughs and in inwardly offset relation to the opposite ends of the fixtures with generally flat external connecting ears projecting therefrom in planes normal to said axis, the contiguous ears of each two adjacent fixtures being disposed in close overlapping relationship and formed with registering slots arcuate about said axis and clamping means adapted to extend through said slots of said overlapping ears for securing said adjacent fixtures in selected positions of angular adjustment.

7. An elongated lamp fixture adapted for assembly with similar fixtures in side-by-side parallel relation to form a bank of an infrared oven, said fixture comprising, in combination, an elongated trough of generally U-shaped cross section supporting electrical fittings along the bight portion thereof for the reception of heating elements therein, the side portions of said trough diverging laterally from its bight portion to define a longitudinal outwardly opening reflector shield, two transverse end plates closing opposite ends of said trough, two generally flat external ears projecting outwardly in opposite directions respectively from the side portions of said trough in planes transverse to said trough and being disposed in inwardly offset relation to the ends thereof, each of said ears having a slot arcuate substantially about the outer longitudinal edge of the associated side portion of said trough whereby a number of said fixtures may be assembled together with their contiguous ears in close overlapping relationship for relative transverse angular adjustment substantially about their contiguous longitudinal edges and secured in selected positions of adjustment by clamping means extending through the slots of said overlapping ears.
